ALARM APPARATUS

Benjamin Goldstone, Long Beach, N. Y.

Application June 30, 1931, Serial No. 547,842

4 Claims. (Cl. 177—314)

This invention relates to alarm systems.

In the operation of burglar alarm systems, or systems of similar character, it has been customary practice to use, for the power source, some means, such as a battery, which, during the effectiveness of the circuit, was subjected to a constant drain. These batteries, therefore, required replacement at frequent intervals, and account for high cost of upkeep as to maintenance, supervision and replacement, as well as possible failure of the system to operate when the batteries deteriorated.

It is an object of the invention to provide a system in which a local power source, such as the common house lighting circuit, may be used as the main or primary power medium for the operation of the system, the system also including a secondary power source which, upon failure of the primary source, becomes immediately active to energize the system without the initiation of an alarm unless there has been tampering with the system in this period. For this purpose, the ordinary house lighting alternating current cables may be used as the primary source, a step-down transformer, if necessary, being interposed to regulate the voltage applied to the circuit. As one element of the system, there is provided a relay which operates so quickly that the "drop", ordinarily used in such systems to complete the alarm circuit, will be delayed sufficiently in its action so that the secondary power source will have become active to energize the coil of the "drop" before its armature could have dropped to create an alarm, thus retaining it uninterruptedly in the normal position of the system where there has been no outside interference.

It is an object of the invention to provide a system of the type described which may be applied both for circuits devised to initiate an alarm when the protective circuit is broken, or when a portion of such circuit is short-circuited.

It is an object of the invention to provide a system of the character set forth in which a control switch, provided to make the circuit effective, is operated in such manner that no alarm will be created by the closing of the switch, when making the system operative, even though the primary source be inoperative at that time.

Other objects of this invention will be herein-after set forth, or will be apparent from the description and the drawings, in which are illustrated a number of embodiments of apparatus for carrying out the invention.

The invention, however, is not intended to be

restricted to the particular constructions and arrangements of parts, the particular applications of such constructions, the specific methods of operation, nor to the various details thereof, herein shown and described, as the same may be modified in various particulars or be applied in many varied relations without departing from the spirit and scope of the invention, the practical embodiments illustrated and described merely being attempts to show some of the various forms and modifications in which the invention might be embodied.

On the drawings, in which the same reference characters refer to the same parts throughout, and in which are disclosed the preferred embodiments,

Fig. 1 is a diagrammatic view of a system embodying the invention.

Fig. 2 is a view, similar to Fig. 1, of a modified system.

Fig. 3 is a similar view of a further modified system.

Fig. 4 is a view in perspective of a switch box with which are associated the principal elements of the circuit.

Considering the system shown in Fig. 1, the dotted lines 10 are intended to indicate the boundaries of a switch box 12, while the dotted lines 14 are intended to indicate the door 16 of that box. In box 12 may be mounted a panel 18 upon which are assembled relays 20, 22 and 24, and also a resistance element 26. On the door is intended to be mounted a switch 28, controlled by any suitable lock mechanism (not shown), and the signal bulbs 30 and 32, visible through suitable openings through the door.

For the operation of this apparatus, there are provided two distinct power sources 34 and 36. Power source 34 is here shown as a step-down transformer for applying the requisite voltage as power is drawn from lines 40. Power source 36 may be a battery. However, it is to be understood that the two power sources may take any desired characteristic form so long as source 34 is of the type capable of supplying substantially unlimited power at all times, and source 36 is of the type not subject to great deterioration owing to the age and from lack of use. The source 36, in this instance, is intended to operate the alarm creating device 44, but it is to be understood that the system might be rearranged so that device 44 would be actuated from source 34 when that source is effective.

Leads from source 34 are carried over to a pair of binding posts 46 and 48 upon panel 18.

From binding post 46, a lead is taken to a point 50 on a bar 52 of switch 28, this bar being moved by the lock mechanism (not shown). The stationary contact 54 opposed to point 50 is connected, by a lead 56, to the coil 58 of relay 20. The other terminal of the coil is led back to binding post 48 by means of a lead 60, which also makes contact with one terminal of resistance element 26. When switch 28 is moved to closed position, a current will flow through coil 58, which will attract an armature 62. This armature is preferably of considerable weight, and is pivoted at 64 so that it will normally tend to fall downwardly at one end to bring a contact finger 68 at the other end into electrical contact with a stop 70.

When coil 58 is energized, the armature will be lifted so that contact fingers 72 and 74 will be brought into engagement with respective stops 76 and 78. A branch lead 80 from lead 56 makes electrical connection with stops 76 and 78, while the armature itself, by a lead 82, is connected to a binding post 84 to which one terminal of the house protective circuit 86 is connected. This protective circuit may be of any general construction, following the well known practice. Its other terminal is connected to a binding post 88 from which a lead is extended to the coil 90 of relay 22, which is commonly known as the "drop". The other terminal of coil 90 is electrically connected with lead 60.

When relay 20 is energized by a current flowing from power source 34, armature 62 will automatically place in circuit with source 34, the series connected drop 22 and the house circuit 86. If circuit 86 be broken, coil 90 will be de-energized. While the coil has been energized, it has attracted an armature 92 forming a part of, or otherwise secured to, a leaf spring 94, one end 40 of which, by lead 96, is connected to a binding post 98 to which one terminal of source 36 is connected. The other terminal of this source is connected to a binding post 100. From this binding post, a lead 102 is carried over to another binding post 104, to which one terminal of alarm device 44 may be connected. The other terminal of the device, which may be the customary gong, is connected to a binding post 108 from which a lead 110 is directed to a stationary contact 112 cooperating with a moving point 114 upon bar 52. This point, by a lead 116, is connected to a post 118 with which the free end of spring 94 will make contact when coil 90 is inactive to draw armature 92 toward it.

When the protective circuit 86 is not energized, spring 94 will switch source 36 into circuit with the gong to initiate an alarm. Of course it is necessary that switch 28 be in closed position in order to effect this. Also, it will be noted that, in order to prevent an alarm when the switch is being closed, it is necessary that coil 90 be energized before the alarm circuit is completed. For that reason, the points on moving bar 52 are arranged so that, in moving the bar toward the stationary contacts, first point 50 will complete its circuit before either one of the others is affected. For this reason, if source 34 is operative, coil 90 will be energized and the circuit of the alarm device broken at post 118 before point 114 electrically connects with contact 112.

However, if power source 34, for any particular reason, is inactive, secondary source 36 must be placed in circuit before the alarm circuit is completed. For this purpose, point 120

upon bar 52 is arranged to connect electrically with its stationary contact 122 before contact 112 and point 114 are electrically connected, and after the circuit has been completed between contact 54 and point 50. Point 120 is connected by a lead 124 with binding post 100, while stationary contact 122 is connected, by a lead 126, to lead 60. The points 50, 120 and 114 preferably are made up as U-shaped spring members, one arm of each being secured to the bar 52.

Stop 70, by means of a lead 128, is connected to lead 98. When armature 62 is resting so that finger 68 is in contact with stop 70, the circuit will be completed from the armature through the post, lead 128, lead 98, source 36, lead 124, the switch, leads 126 and 60, coil 90, protective circuit 86, lead 82, to the armature, thus energizing relay 22 in the same manner as was done by power source 34. It will be seen that if, after power source 34 has been made active, it should fail for any reason, the weighted armature 62 will operate to bring finger 68 into electrical connection with stop 70, completing the circuit of source 36. As can readily be noted, there is a wide difference in weights between armatures 62 and 92. Armature 62, as it moves about its pivot 64, and especially in the downward movement under gravitational force, will have a greater force to overcome such retarding forces as friction at its pivots than armature 92 will have to overcome retarding forces acting upon it, such as the resiliency of spring 98. The retarding tension upon spring 94 and its sustained position, by adjustment of post 118 and the upper stop post 130, are regulated so that, upon fall 35 of armature 92, the period of time necessary for spring 94 to make contact with post 118 will be greater than that necessary for armature 62 to move finger 68 into contact with stop 70; the circuit of source 36 will, therefore, have been completed before spring 94 will have had the opportunity to complete the circuit for alarm device 44.

Relay 24 provides a holding circuit for retaining the alarm circuit energized, once a break has been made in the protective circuit, even though the break may have been repaired. Branch leads 132 and 134 are taken from binding posts 104 and 108, respectively, to the coil 136 of relay 24. Should the protective circuit be broken and the alarm circuit energized by the fall of armature 92, a portion of the same current which would pass through alarm device 44 will act to energize coil 136, attracting armature 138 which is secured to a spring finger 140, secured between a tension adjusting means 142. Normally the free end of finger 140 rests upon a stop 144. When coil 136 is energized, however, this finger will be lifted into contact with a post 146, which, by a lead 148, is connected to lead 116. With coil 136 energized, current from source 36 will flow through lead 96, branch lead 150, spring finger 140, contact post 146, leads 148 and 116, the switch, and then will divide, after lead 119, to pass through alarm device 44 and coil 136, and back to source 36 through lead 102. In other words, coil 136 will maintain its own energizing circuit as well as the energizing circuit for the alarm device.

In order to indicate to the user which of the two power sources is active, bulbs 30 and 32 are provided, bulb 30 being intended to indicate that primary source 34 is operative, and the bulb 32, the other source. One terminal of bulb 30 is connected, by a lead 152, to resistance element 75

26, while the other terminal, by a lead 154, connects with lead 56 and stationary post 54. Its circuit will, therefore, be completed through lead 152, resistance 26, lead 60, source 34, the switch, and leads 56 and 154.

5 In order to light bulb 32, there is provided, in conjunction with relay 20, an armature 156, preferably disposed at the end of coil 58 opposite armature 62. Armature 156 is mounted upon a spring finger 158, which normally tends, under the action of tension adjusting mechanism 160, to make electrical contact with post 162. Post 162, by a lead 164, is connected to one terminal of bulb 32, while the anchor post 166 for spring 10 158 is connected, by a lead 168, to binding post 98. When coil 58 is not energized by power from source 34, the circuit from bulb 32 will be completed through lead 164, post 162, spring 158, lead 168, source 36, lead 124, the switch, to the bulb 20 through leads 126 and 170.

It will be noted that, when power source 34 becomes inactive, the battery source is immediately placed in circuit to operate the entire apparatus, without the danger of initiating an 25 alarm unless there has been tampering with the protective circuit. Also, during the action of power source 34, battery source 36 is so protected that no part of the current from source 34 will pass therethrough, and, therefore, will be 30 unable to effect deterioration of such cells as normally make up battery power sources.

In Fig. 2 has been shown apparatus whereby the alarm will be initiated not only by breaking a portion of the alarm circuit, but if a short circuit of any portion thereof should be effected. 35 In this apparatus, there is provided a panel 172 upon which are mounted the operating elements of the relay switching circuits, and a door 174 for carrying a switch 176, similar to switch 28 40 in its structure. Upon the panel are mounted relays 178, 180 and 182. One terminal of coil 184 of relay 178 is connected, by a lead 186, to a binding post 188 to which one terminal of the primary source 190 is connected. The other terminal of source 190 is connected to a binding post 192, which, by a lead 194, is connected to a stationary post 196 opposite a moving point 198 45 on bar 200 of the switch. This point, by a lead 202, is connected to the other terminal of the coil.

50 When coil 184 is energized, it attracts an unbalanced armature 204 to bring fingers 206 and 208 into electrical connection with their respective stop posts and 210 and 212. These posts, by a lead 214, are connected to, and receive power 55 from lead 186 and transmit it through the armature to a lead 216, led from the armature to a point 218 upon bar 200. The complementary stationary post 220 is connected by a lead to a binding post 222 upon the panel which constitutes 60 one terminal of a portion 224 of the protective circuit 226. The other terminal of this portion is carried to a binding post 228 from which a lead is connected to coil 230 of relay or drop 182.

The other terminal of the coil is connected to 65 lead 232, extending to a binding post 234 forming a terminal for the other portion 236 of the house protective circuit. Portion 236 is also connected to a binding post 238 which is electrically connected to lead 194. The circuit of the house 70 protective circuit, therefore, consists of power source 190, leads 186 and 214, posts 210 and 212, armature 204, lead 216, the switch, binding post 222, portion 224, coil 230, lead 232, portion 236 and lead 194. Any break in the house protective 75 circuit will deenergize the coil 230; also, any

short circuit between portions 224 and 236 will prevent the passage of current through, and thus effect deenergization of, coil 230.

Coil 230, upon energization, attracts an armature 240, fixed to a spring member 242, anchored at 244 and electrically connected, by a lead 246, to a binding post 248 which provides one terminal for a secondary power source 250. The other terminal of this power source is connected to a binding post 252 which is also connected to 10 a binding post 254, providing one terminal for a gong or similar device 256. The other terminal of the gong is connected, by a lead 258, to a binding post 260 from which a lead 262 is taken to the stationary contact 264 opposite the 15 point 266 of the switch. A lead 268 then makes connection with a post 270 with which spring member 242 makes contact when coil 230 is not active to attract armature 240. When the circuit of gong 256 has been completed by the fall 20 of armature 240, coil 272 of relay 180 is also energized from the branch circuit consisting of a lead 274 connecting with post 254, and a lead 276 connecting with binding post 260.

When coil 272 is energized, it attracts its armature 278 to bring a spring finger 280 into contact with a post 282 which is connected, by a branch lead 284, to binding post 260. When there has been any interference with the system at the portions of the house protective circuit, and the 30 drop has been actuated to complete the circuit between member 242 and its complementary post, and gong 256 has been actuated, coil 272, by this branch circuit, will have become energized to attract armature 278. Thereupon, power will flow 35 from source 250 to spring finger 280, post 282, and lead 284, and then will divide to pass through gong 256 or through lead 276, coil 272, lead 274, back to the source. Coil 272 thus constitutes 40 its own holding means for its own circuit to retain the gong ringing.

If power source 190 should become inactive, armature 204 will bring finger 208 into contact with post 218 from which a lead 290 connects with lead 246. In this position, source 250 will 45 serve to operate drop 182 in the same manner as did power source 190.

In order to prevent the initiation of an alarm upon closing the switch, points 198, 218 and 266 are arranged to make their contacts with the 50 respective stationary contacts so that, first power source 190 is placed in circuit, then the protective circuit, and finally the gong or alarm circuit. In other words, before source 250 may become active, power source 190 must have been 55 placed in circuit, and the house circuit also completed so that there should arise no possibility of activity on the part of the drop to create an alarm. Bulbs 292 and 294 are provided, and they are wired similarly to those of Fig. 1, to indicate 60 which of the two sources is active.

In the arrangement shown in Fig. 3, relays 296, 298, 300 and 302 are arranged upon panel 304, while upon door 306 is assembled a switch 308, similar in structure to the switches of the 65 other constructions. In this arrangement, a primary power source 310 has its terminals connected to binding posts 312 and 314 upon the panel. From binding post 312 there is led a trunk 316 from which branch leads 318 and 320 70 tap a supply for relays 296 and 298, respectively. The other terminals of these relays are connected to a trunk 322 which is led around, through a binding post 324, to a point 326 on the moving bar 328 of the switch. This point is intended to 75

make contact with a stationary contact 330 from which a trunk 332 leads to a binding post 334 upon the panel, and then to binding post 314.

By this means, the two relays, upon closing the switch, are energized to attract their respective armatures 336 and 338. Each of these armatures is pivotally mounted in unbalanced condition, so that, when the relays are not energized, they will assume the positions indicated in Fig. 3. For armature 336, this position would bring a spring finger 340 into contact with a stop post 342, while for armature 338, a spring finger 344 is brought into contact with a stop post 346. When relays 296 and 298 are energized, armatures 336 and 338 are active to break the connection between spring fingers 340 and 344 and their respective stop posts. Armature 336, by such movement, will be energized to bring spring finger 348 into contact with a stop post 350.

Armature 338 carries two spring fingers 352 and 354 which, when relay 298 is energized, will be pressed into contact with stop posts 356 and 358, respectively. These stop posts are connected by a branch lead 360 with trunk 316, while armature 338 itself is connected, by a lead 362, with a binding post 364 which forms one terminal for a portion 366 of the house protective circuit 368. The other terminal of this portion is connected to binding post 370, which, by a lead 372, is connected to relay 300. A lead 374 from this relay is connected to binding post 376 forming a terminal of the other portion 378 of the house protective circuit. The other terminal of this portion is at binding post 380 from which a lead 382 is directed to make electrical connection with armature 336.

When relays 296 and 298 are energized by power source 310, current will flow from the power source, through trunk 316, branch lead 360, stop posts 356 and 358, armature 338, lead 362, portion 366, lead 372, relay 300, lead 374, portion 378, lead 382, armature 336, post 350, trunk 322, the switch, trunk 332, to the power source.

If any break be made in either of portions 366 or 378, or if an attempt be made to create a short circuit between these two portions, relay 300 will be deenergized, resulting in the fall of armature 384, which is carried by a spring 386, the end of which has been retained by the armature against stop 388. This spring, by a lead 390, is connected to the stationary contact 392, the moving point 394 of which is connected, by a trunk 396, to binding post 398 forming one of the terminals for a secondary power source 400. The other terminal 402 of this power source is connected to the moving point 404 opposite the stationary contact 406 on the switch. From contact 406, a lead 408 is connected to post 410 which is the terminal of gong 412. The other terminal of 60 the gong is connected to binding post 414 which, by a trunk 416, is connected to stop post 418 against which spring 386 abuts when relay 300 is deenergized.

Thus, when relay 300 is deenergized, spring 386 will close the circuit from source 400 through the switch, lead 408, gong 412, trunk 416, post 418, spring 386, lead 390, the switch, and trunk 396. In order to hold the ringing circuit closed after a break or other interference with the protective circuit has occurred, relay 302 is energized by a branch lead 420 leading from trunk 422 which is connected to binding post 410. The other terminal of relay 302 is connected, by a lead 424, to post 414. In other words, when the gong is energized by the fall of armature 384, relay 302 will

also be energized by its branch circuit to attract armature 426, carried upon spring 428 which normally rests upon stop 430. When attracted by the relay, spring 428 will make electrical connection with a stop 432, which, by a branch lead 434, is connected to trunk 416. Spring 428 itself, by a branch lead 436, is connected to trunk 396. This holding circuit is substantially similar to that of the arrangements previously described.

If power source 310 should become inactive, armatures 336 and 338 will drop. In such case, fingers 340 and 344 will be brought into electrical connection with their respective stop posts 342 and 346. Now, current will flow from battery 400 through the switch, lead 408, trunk 422, stop post 342, armature 336, lead 382, portion 378, lead 374, relay 300, lead 372, portion 366, lead 362, armature 338, stop post 346, trunk 438 back to the battery. Now, if any break or short circuit be made in, or across the protective circuit, relay 300 will be deenergized in the same manner as if power source 310 had been active, actuating gong 412 in the same manner.

Indicating light bulbs 440 and 442 are provided and indicate respectively whether power source 310 or source 400 is operating to pass current through the house protective circuit. Bulb 440 is in circuit with resistance unit 444, which, by a lead 446, is connected to binding post 312. The other terminal of the bulb is connected to trunk 322 by a lead 448 so that, when source 310 is operating, bulb 440 will be lighted.

When source 310 is inoperative, relay 298 will no longer attract an armature 450 upon a spring 452, which is so tensioned that, in normal relation, it will be in contact with a stop post 454. However, relay 298, when source 310 is effective, will pull the spring away from this stop post. The spring itself is connected to trunk 422 by lead 456, while the stop post, by a lead 458, is connected to the bulb. The other terminal of the bulb is connected to trunk 438 by a lead 460.

The points 326, 404 and 394 are arranged to make contact with their respective contact posts in the order named for purposes previously indicated.

Many other changes could be effected in the particular apparatus designed, and in the methods of operation set forth, and in the specific details thereof, without substantially departing from the invention hereof which is intended to be defined in the accompanying claims, the specific description hereinabove being set forth merely to illustrate operative embodiments for carrying out the spirit of the invention.

What is claimed as new and useful is:—

1. In alarm apparatus, a protective circuit, alarm-producing means, an alternating current power source, a direct current power source, a switch-over relay, a heavy armature for the switch-over relay pivotally mounted in an unbalanced state, the armature being in the protective circuit, the switch-over relay normally being energized by the alternating current power source to maintain the armature raised against gravitational force and thus to keep the armature and the protective circuit in circuit with the alternating current power source; the armature comprising means, when the alternating current power source is deenergized, to move to cut the alternating current power source out of circuit with the protective circuit and the armature, and to bring the direct current power source into circuit with both armature and protective circuit; and a

drop relay in the protective circuit, the drop relay having a relatively light armature for controlling the alarm-producing means, the movements of the armatures for making or breaking their circuits being limited, the limits of the movements being defined so that, in such circuit-making or circuit-breaking movements, they will, at substantially the same instant, be freed for movement, but the switch-over relay armature will 10 complete its circuit before the drop relay armature may become effective.

2. In alarm apparatus, a protective circuit, alarm-producing means, an alternating current power source, a direct current power source, a 15 switch-over relay normally energized by the alternating current source; the protective circuit including a drop relay and means normally tending, under the force of gravity, to energize the protective circuit from the direct current power 20 source but, under the normal energization of the switch-over relay, being controlled to energize the protective circuit from the alternating current source; means actuated by the drop relay for controlling the alarm-producing means, the 25 drop-relay-actuated means normally tending under the force of gravity to make the alarm-producing means effective, the protective-circuit-energizing means including a pivoted member of such large mass that gravity acts with greater 30 force to turn it about its pivot than the forces acting upon the drop-relay-actuated means to move it to circuit-closing position, the turning of the pivoted member about its pivot and the action of the drop-relay-actuated means being limited, the limits and the relation between the action of the forces of gravity being such that the pivoted member will have completed its movement before the drop-relay-actuated means can 35 make the alarm-producing means effective.

40 3. In alarm apparatus, a protective circuit, alarm-producing means, an alternateing current power source, a direct current power source, a switch-over relay normally energized by the al-

ternating current power source, means controlled by the switch-over relay in accordance with the energy derivable from the alternating current power source for determining whether the alternating current power source or the direct current power source shall energize the protective circuit; the means controlled by the switch-over relay comprising means, when energy for the switch-over relay is not derived from the alternating current power source, to cut the alternating current power source out of circuit with the protective circuit, and to bring the direct current power source into circuit with the protective circuit; and switching apparatus for first switching on the alternating current power 15 source, thereafter making the direct current power source effective, and then making the alarm-producing means effective so that it may produce an alarm under control of the protective circuit. 20

4. In alarm apparatus, a protective circuit, alarm-producing means, an alternating current power source, a direct current power source, a switch-over relay normally energized by the alternating current power source, means controlled 25 by the switch-over relay in accordance with the energy derivable from the alternating current power source for determining whether the alternating current power source or the direct current power source shall energize the protective circuit; the means controlled by the switch-over relay comprising means, when energy for the switch-over relay is not derived from the alternating current power source, to cut the alternating current power source out of circuit with the protective circuit, and to bring the direct current power source into circuit with the protective circuit; and switching apparatus for first switching the power sources to make them effective for the control of the means controlled by the switch- 30 over relay before the alarm-producing means may be made effective. 35
